UNITED STATES PATENT OFFICE.

S. P. GILBERT, OF RACINE, WISCONSIN.

HOLLOW AUGER.

Specification of Letters Patent No. 31,883, dated April 2, 1861.

To all whom it may concern:

Be it known that I, S. P. GILBERT, of Racine, in the county of Racine and State of Wisconsin, have invented a new and useful Improvement in Tubular Augers; and I do hereby declare that the following is a full, clear, and exact description thereof, reference being had to the accompanying drawings, making a part of this specification, in which—

Figure 1 represents a plan view of a machine constructed to bore wooden pipes. Fig. 2 is a longitudinal vertical section taken through the machine of Fig. 1.

Similar letters of reference indicate corresponding parts in both figures.

To enable those skilled in the art to make and use my invention, I will proceed to describe its construction and operation.

A is a suitable frame upon which the auger, the machinery for operating it, and the logs to be bored are supported. On one end of this frame A are suitable guide ways for the log blocks B B, which blocks are secured to a carriage B' which can be moved in a direction with the length of the log B² either back or forth by means of a rack and pinion as shown in Fig. 2 of the drawings or by any other suitable means. The log blocks B B may be made perpendicularly adjustable so that the axis of the log may be brought in a line with the axis of the auger. The journal boxes b b support the rear end of a cylindrical case C and the journal boxes d, d support the rear end of a tube G which tube G extends out behind the rear end of cylindrical case C.

D is the cutter or bit secured to the front end of the tube G and rotated thereby.

The cylindrical case C, central tube G and bit D form my improved auger or implement.

Between the journal boxes b b is a belt wheel F which gives a rotary motion to the case C in one direction while the belt wheel e between boxes d d gives rotary motion to the tube G in an opposite direction to that of the case C. The wheels F and e are rotated by bands which communicate with a driving shaft H; one of the bands is crossed and this is what transmits a right and left rotary motion to the case C and tube G from one shaft.

E is a sliding block which projects up from frame A between the carriage B' and the boxes b, b and supports the tubes C and

G keeping them steady and well directed to the work. This block E may be attached to the carriage B' so as to move with it or it may be moved by hand, or in any convenient way. The block E should have a steady and firm support on frame A and the case C should be allowed to turn freely in the journal box in this block, E.

The bit D is somewhat larger in its diameter than the case C over the end of which it slips; and the bit has a central short tube g over which the end of tube G fits as shown in Fig. 2. The end of bit D is furnished with cutting lips like any bit of this description which perform the cutting and discharge the chips through the bit between the outside of the tube G and the case C and these chips are received by a screw thread or worm a which is formed around the outside of tube G. By this worm the chips are carried back and discharged from the rear end of case C as represented in red lines Fig. 2.

The cylindrical bit D does not cut to its center but it leaves a solid core a which, as the boring progresses passes through the tubular carrier G as shown in Fig. 2 while the chips pass on the outside of the tube between the case and the tube. The short central tube g of bit D is smaller in its diameter than the inside of tube G into the end of which it fits so that the core a will not touch the sides of the tube G and cause friction, as this core is smaller than the bore of this tube. 90 This is also the case with the bit D and case C, the former being larger than the latter the case C will not touch the sides of the hole in the log providing that the implement is guided straight through the center of the log.

The operation of the entire machine is as follows: The log is properly set and adjusted on its blocks B, B so that the axis of the log will be in a line with the axis of the tube G and the case C, which are concentric. The tube G and case C are now rotated in opposite directions. The bearing block E is adjusted so that the end of case C is steadied and the end of the log is then advanced to the work by turning the crank h which is on the pinion shaft i. As the work of boring progresses the carriage will push the bearing block E along, which block steadies and supports the case C in a true center with the log. It will thus be seen that the central tube G is supported at both of its ends. It

will also be seen that the case C is supported at both ends, at one end in its journal boxes b b and at the other end in its traveling support E. The boring of very long logs 5 may thus be accomplished with my machine with comparatively little friction and in the most accurate manner. If no exterior case were employed it would be difficult to guide the auger properly, because the edges of the 10 spiral worm can give no suitable support for that purpose. But by employing a rotary case the implement may be set and guided so as to bore with perfect accuracy, no matter what the character of the wood to which it is 15 applied; and the chips will also be more easily and freely discharged as the work progresses.

I do not claim the invention of a hollow boring cylinder, which leaves no core, as patented by Wyckoff. Nor do I claim the invention of a hollow core forming auger, as patented by Stevens. But

Having described my invention what I claim and desire to secure by Letters Patent is—

25 The combination with the bit D and hollow auger G of the rotary case C, substantially as and for the purposes herein shown and described.

S. P. GILBERT.
